WATER CLOSET

William H. Armstrong, Bloomfield Hills, Mich., assignor
to Borg-Warner Corporation, Chicago, Ill., a corpora-
tion of Delaware

Filed Dec. 26, 1968, Ser. No. 15,120

Term of patent 14 years

Int. Cl. D23—02

U.S. Cl. D23—65

FIG.1

FIG.2

FIG. 1 is a perspective view taken from the front, top and left side of a water closet showing my new design; and

FIG. 2 is a perspective view taken from the front, top and left side thereof.

The dominant features of my design reside in the portions shown in full lines.

I claim:

The ornamental design for a water closet, substantially as shown and described.
